(57) **CLAIM**

The ornamental design for a retail fixture group, as shown and described.

DESCRIPTION

This application incorporates by reference in its entirety each of the following U.S. Design Patent Applications:

Application Ser. No. 29/655,963, filed Jul. 9, 2018, titled “Retail Fixture”

Application Ser. No. 29/655,967, filed Jul. 9, 2018, titled “Retail Fixture”

Application Ser. No. 29/655,973, filed Jul. 9, 2018, titled “Retail Fixture”

Application Ser. No. 29/656,127, filed Jul. 10, 2018, titled “Retail Fixture”

Application Ser. No. 29/656,129, filed Jul. 10, 2018, titled “Retail Fixture”

FIG. 1 is a front right perspective view of a retail fixture group showing the claimed design;

FIG. 2 is a front left perspective view thereof;

FIG. 3 is a front plan view thereof;

FIG. 4 is a rear plan view thereof;

FIG. 5 is a left side plan view thereof;

FIG. 6 is a right side plan view thereof; and,

FIG. 7 is a top plan view thereof.

The broken lines in the figures show portions of the retail fixture group that form no part of the claimed design.
